UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,809, dated March 14, 1882.

Application filed February 11, 1882. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A and B are two fan-like flower figures, with small projecting star and leaf forms, depending from opposite ends of a horizontal bar, a, having somewhat-symmetrically-projecting figures of irregular leaf and conventional forms, among them the leaf b and connected cup-shape form c on the left and the irregular form d on the right. Supporting the bar a, and above it, is the spreading flower figure C, with small buds or cross-like projections characteristic of many figures of this design. Connected with C, and above it to the right, is the shield-shaped form D, with projecting leaves. Above C, on the same shaft, is the large circular figure E. From E on the right projects upward the group F, a conical figure with leafy base and leaves below, and a projecting bud form above. From E above projects the group G, consisting of a recurring stem bearing a cup-shaped figure and a larger conical flower, and a shaft above and below, with connected parts and small projections, as shown.

H is a symmetrical rectangular figure with short projecting stems on each side bearing the conical flower and bud groups e and f. Connected with H is the figure K, resembling a circular form, holding the large flower figure L, (shown in part at each end of the photograph,) with a circular leaf base, a conventional center, and surrounding leaves, and with a small rectangular figure on a stem to the left. From the lower part of K project laterally and upward short stems bearing on the left the group z, consisting of an oblong figure bearing above a cup-shaped flower and bud, and on the right the group g, consisting of a similar oblong figure with small circular star-shaped and pointed flower and leaf forms.

M is a large figure with shield-shaped cen-

ter, surrounding leaf forms above, and angular forms below. On the left project below a small rectangular form, in the middle a pointed figure, h, and above a tapering leaf and flower figure, i, with a rosette at its base. On the right, below, projects a stem bearing a scalloped figure and the fan-like figure j, having a leaf group at its base, and above a figure similar to i, with connected circular flower and leaf forms. Above M is the figure N, consisting of a vertical shaft springing from the horizontal support and widening into a vase-like form. Above N, and supported by it, is the large heart-shaped figure O, with fringing leaves below and projecting small buds and flowers. From O, on the left, springs a group, k, consisting of a drooping stem bearing a circular and a heart-shaped flower figure, and on the right a group, l, consisting of a similar stem bearing a heart-shaped flower with leafy base and connected small flowers and leaves. Above O is the group P, which consists of the large circular rosette-like figure Q, with small projecting circular flowers and buds; below Q a circular form and two horizontal bars inclined downward at their ends, with connected shield-shaped forms on each side surrounded by leaves, and with a projecting bud form on one side, and above Q an open figure, R, with hexagonal base and conventionalized vertical bars and leaf forms above.

S is a group, shown in part on each side of the photograph and extending the entire length of the same. It consists of a sinuous stem or vine or support, m, of varying thickness, and the various groups and figures, large and small, projecting from such support into the adjacent field on both sides of m. On the left of m is the group n, being a stem bearing a small open flower and leaf cluster, and a larger figure having a circular flower as its center, and surrounding leaves and projecting bud. Above is the group o, being a heart shape in a leaf cluster, from which projects a stem bearing a flower. Above is the group p, being a stem bearing a small three lobed flower on one branch, and a large conical leaf-group with a circular flower at its center. On the right of m is the group q, consisting of an angular stem bearing, with various smaller projections, an open flower figure, a larger conical leaf figure, r, with a circular flower center and various small cross-

like projections, and a pointed figure with a leaf base and projecting bud. Above is the five-leaved-flower figure *s*. Above *s* is the group *t*, consisting of a large bulb-like figure 5 with a pendent stem bearing a small flower and leaves.

- u* is a group above *t*, consisting of a stem bearing the bulb-like flower *v*, with small wing-like leaves and the fan-shaped flower *w*.
10 *x* is a small group above *u*, and is shown in part at each end of the photograph. It consists of a stem bearing a small truncated cone, and a pointed figure, *y*, with small leaves at its base.

T is an irregular group of small geometric and flower figures. 15

I claim—

The design for carpets, consisting of the groups and figures A B C D E F G H K L M N O P Q R S T a b c d e f g h i j k l m n o p q r s t u v w x y z and connected parts, substantially as shown. 20
